UNITED STATES PATENT OFFICE.

ROBERT J. EKE, OF LONDON, ENGLAND.

MACHINERY FOR DECORTICATING VEGETABLE FIBERS.

SPECIFICATION forming part of Letters Patent No. 633,507, dated September 19, 1899.

Application filed December 30, 1897. Serial No. 664,542. (No model.)

To all whom it may concern:

Be it known that I, ROBERT JAMES EKE, a subject of the Queen of Great Britain and Ireland, residing at 34^a White Lion street, Pen-
tonville, London, England, have invented an
Improvement in Brakes, of which the following
is a specification.

My improved brake is especially designed
for the decortication of rhea. Before my in-
vention, so far as I am aware, no machine
was ever produced which would successfully
accomplish this object, although many efforts
have been made in this direction, the reason
being that on account of the peculiar struc-
ture of rhea the ordinary brakes will not suc-
cessfully treat it.

The ordinary method of treating rhea by
machinery is to pass it through plain rollers
and then through breaking-rollers and beat-
ers. The plain rollers crush the stem, thus
embedding the woody portion of the stem in
the bark, epidermis, and gum. The break-
ing-rollers then break the stems across, and as
the woody portions are cemented to the bark
they break the bark, and with it the fiber con-
tained therein. It has also been proposed to
split the stems; but so far as I am aware no
machine, prior to my invention, has been de-
vised which will do this successfully.

Rhea has been successfully decorticated by
hand by stripping the bark and fiber from
the woody stick. The expense of this method
has prevented it from coming into general
use.

The object of my invention is to imitate by
machinery this hand process, and this object
I have perfectly attained by means of the
machine described and shown.

My invention consists in the construction
and combination of parts, as hereinafter de-
scribed and claimed.

In the accompanying drawings, Figure 1 is
a side elevation of my improved brake. Fig.
2 is a side elevation of part of the splitting-
rollers. Fig. 3 is an end view of the same.
Fig. 4 is a diagrammatic representation of
the driving-gear. Fig. 5 is a plan view of the
driving-gear. Fig. 6 is a side view of the
beaters. Fig. 7 is a side view of the break-
ing-rolls; and Fig. 8 is a plan view of the ma-
chine, the gearing being omitted.

The same letters and numerals denote the
same parts in all the figures.

a a show the standards of the machine, *b b*
the rollers for splitting or wedging open the
stalks as they are fed into the machine. A
plan of a portion of these rollers is shown at
Fig. 2, drawn to an enlarged scale, showing
their position in respect to one another when
fitted in the machine. It will be seen that
the edges *c* of the circumferential **V**-grooves
are rounded, so that the stalks may not be
cut, but only wedged open longitudinally.
It will also be observed that the rollers *b b*
do not touch at any part. 65

d d show the rollers for breaking the stalks
transversely after they have been wedged
open by the rollers *b b*. I may have the
grooves on the rollers *d d* of any suitable form,
and I prefer to have both the rollers provided
with longitudinal **U**-grooves (see Fig. 7) or
V-grooves. 70

e e show the beaters. These are provided
with blades which intermesh, as shown at
Fig. 6, detached. The edges *f* of the blades
are rounded, so that the fiber may not be cut. 75

g g show the tension-rollers, which I prefer
to have grooved longitudinally in the same
way as the rollers *d d*.

h shows the feeding-table or endless band,
and *i* the delivery-table or endless band.
These tables or bands travel on the rollers
k k l l, respectively.

The beaters *e e* are caused to rotate at a
high speed by means of the pinion *m*, which
engages with a spur-wheel *n*, keyed on the
pulley-shaft *o*. On the shafts of the rollers
b b are keyed spur-wheels which engage with
one another, so that one of these rollers is
driven by the other. Onto each of the shafts
k k l l, respectively. 80
of the rollers *d d*, *e e*, and *g g* is likewise keyed
a coupling-wheel, so that each of the upper
rollers is connected with a corresponding
lower one. These coupling-wheels are not
shown on the drawings. The splitting-rollers
b b and beaters *e e* are adjusted by the han-
dles 10. 90

9 shows a shield for preventing the woody
portions from mixing with the treated fiber
on the table *i*. 100

The bearings *r s t u* slide in pockets *r' s' t'*
u' in the frame *a*, so that the rollers *b b d d*,

beaters *e e*, and tension-rollers *g g* can be adjusted according to the nature of the fiber to be treated, as the different fibers require more or less pressure exerted on them.

5 *v* shows springs pressing on bearings *s* and *u*. The action of a machine constructed as above is as follows: The pulley-shaft *o* is driven by suitable means. The pinion *p* engages with the spur-wheel *q*, which is keyed 10 on the shaft *5* of the bottom splitting-roller *b*, which insures this pair of rollers *b b* rotating. The spur-wheel *w* on the shaft *5* engages with the idle-wheel *x*, (see Fig. 4,) and thus drives the spur-wheel *y* on the shaft *6*, 15 thereby actuating the pair of breaking-rollers *d d*. Another spur-wheel *z* is also keyed on the shaft *6*, and this spur-wheel gears with another idle-wheel *z'* and so transmits motion to the spur-wheel *y'* keyed on the shaft *8*, 20 thereby actuating the pair of tension-rollers *g g*. The roller *k* is provided with a sprocket-wheel *k'*, connected by means of a chain *x'* with another sprocket-wheel *w'*, keyed on the shaft *5*. The system of gearing between the various 25 rolls is not shown in Fig. 8, but is an ordinary toothed gearing, suitably arranged for driving the rolls in their proper directions or in respect to each other, as will be readily understood by reference to Figs. 4 and 5. The stalks are 30 fed onto the band or table *h* and are then carried to the rollers *b b*. The stalks enter the grooves of the upper and lower rollers *b b* and are wedged open as they pass between the said rollers. They are then conveyed to the

rollers *d d*, where they are broken transversely, and in this form are carried between the beaters *e e*, where, on account of the interior being exposed, the woody portions are beaten out, and the fiber then passes between the tension-rollers *g g* and is delivered onto 35 the band or table *i*.

I have found that it is necessary to set the beaters *e e* as close as possible to the tension-rollers *g g*, so that the ribbons may be cleaned 40 right to the end.

45 I may have additional pairs of beaters and tension-rollers if found desirable.

If desired, the fiber treated as above can be passed through the machine a second time; but this will not be found necessary as a rule. 50

What I claim, and desire to secure by Letters Patent, is—

In a brake, the combination of a conveyer, and two rolls, *b*, one above the other, provided with similar circumferential grooves and elevations, the edges of the grooves and elevations being rounded, and said rolls being so located that the convex portions of one roll enter the concave portions of the other roll, but so that the surfaces of the rolls are not 55 in contact, with breaking-rolls, beaters and drawing-rolls, all the parts being arranged in the order mentioned, substantially as described.

R. J. EKE.
